APPARATUS FOR HANDLING SHEETS

Leonard Baker, Hillsdale, N. J., and Leo C. Williams and George A. Martin, Pearl River, N. Y., assignors to Dexter Folder Company, Pearl River, N. Y., a corporation of New York

Application February 8, 1941, Serial No. 377,974

48 Claims. (Cl. 271—69)

This invention relates to handling sheets of material and while capable of general use is particularly adapted for association with a printing or coating machine and drying oven unit for metal sheets.

One object of the present invention is to provide an improved apparatus which will positively and efficiently feed stiff sheets laterally and in standing or on edge position from a supply thereof conveyed standing on edge one behind another through a drying oven, and advance said sheets in like manner for further handling thereof.

Another object of the present invention is to provide an improved apparatus which will feed stiff sheets laterally and in standing position from a supply thereof conveyed standing on edge one behind another through a drying oven, and deliver said sheets in horizontal or flatwise position to sheet receiving means.

Another object of the present invention is to provide an improved apparatus which enables the feeding of printed or coated sheets of stiff material laterally and in standing position from a drying oven conveyor and delivering of said fed sheets in horizontal or flatwise position to sheet receiving means without likelihood of scratching or marring the printed or coated surface of the sheets.

Another object of the present invention is to provide an improved apparatus whereby printed or coated sheets of metal conveyed through a drying oven standing on edge one behind another may be fed laterally therefrom and in standing position and delivered to sheet receiving means in horizontal or flatwise position with the printed or coated surface of the sheets uppermost.

Another object of the present invention is to provide an improved apparatus adaptable to any situation where it is desired to feed sheets of metal, cardboard, paper and other non-metallic material laterally and in standing position from a supply of such sheets standing on edge one behind another.

Another object of the present invention is to provide an improved suction sheet forwarding device so constructed that vacuum may be utilized to actuate said device in the sheet forwarding direction to forward sheets successively from a supply thereof.

These and other objects of the present invention will appear as the following description thereof proceeds and in order to more clearly understand said invention reference may be had to the accompanying drawings which illustrate one embodiment thereof.

In said drawings:

Fig. 1 is a side elevation of a printing or coating machine and drying oven unit embodying the present invention;

5 Fig. 2 is a fragmentary top plan view of said unit looking from the top and right thereof and showing sheet conveying and positioning devices;

Fig. 3 is an end view of said unit looking from the left to Fig. 1;

10 Fig. 4 is an enlarged broken or fragmentary side elevation of sheet forwarding, advancing and receiving means embodying the present invention;

Fig. 5 is an enlarged horizontal sectional view 15 of a suction sheet forwarding device;

Fig. 6 is an enlarged side elevation, partly in section, of valve means for controlling the operation of the suction sheet forwarding device;

Fig. 7 is a fragmentary end view looking from 20 the right of Fig. 4, with parts omitted for purposes of clearer illustration, showing mechanisms for imparting reciprocating motion to the sheet forwarding device, and for controlling the operation of a sheet supporting and guiding device, 25 respectively;

Fig. 8 is an enlarged top plan view of magnetic sheet advancing devices and supporting and driving means therefor;

Fig. 9 is a horizontal sectional view on the line 30 9—9 of Fig. 4;

Fig. 10 is an enlarged fragmentary top plan view, partly in section, of the sheet supporting and guiding device and driving and control means therefor;

35 Fig. 11 is an enlarged side elevation, partly in section of the sheet supporting and guiding device and driving and control means therefor shown in Fig. 10, with parts omitted for purposes of clearer illustration; and

40 Figs. 12 to 14 inclusive, are side elevations illustrating diagrammatically the action of the sheet supporting and guiding device on an advanced sheet in process of delivery to the sheet receiving means.

45 Referring to the drawings, and wherein like reference characters designate like parts throughout the several views, the present invention is illustrated in connection with a unit for applying a decoration in ink or a coating of other material to sheets of metal, and thereafter heat treating said sheets to dry the material applied to a surface thereof. As shown in Fig. 1 of the drawings, this unit comprises a printing or coating machine indicated broadly at 5, a drying oven indicated broadly at 6, and a conveyor indi-

55

cated broadly at 7 for receiving and conveying the sheets from said printing or coating machine to said drying oven.

The printing or coating machine 5 is the usual type comprising side frames 8 bolted or otherwise suitably secured to the machine foundation, and a pair of printing or coating cylinders 9 and 10 journaled in said frames and between which the sheets pass to receive a decoration in ink or the like or a coating of other material on the upper surface thereof. The movable parts of the machine 5 are operated by an electric motor 11 which is bolted or otherwise suitably secured to the machine foundation. Electric current is supplied to the motor 11 from any suitable source and starting and stopping of said motor is effected by suitable switch means (not shown). The motor 11 has fixed on the armature shaft thereof a pulley 12 around which passes a belt 13 that also passes around and drives a pulley 14 which is fixed on and drives a shaft 15. The shaft 15 extends transversely of the machine 5 and is journaled in suitable bearings in the side frames 8 thereof.

The shaft 15 has fixed thereon and driven thereby a spur pinion 16 which meshes with and drives a spur gear 17 that is fixed on a shaft 18 which extends transversely of the machine 5 and is journaled in suitable bearings in the side frames 8 thereof. The spur gear 17 meshes with a spur gear 19 that is fixed on the cylinder 10 and serves to drive the same. The spur gear 19, in turn, meshes with and drives a spur gear 20 which is fixed on and drives the cylinder 9.

The printed or coated sheets discharged in succession from the machine 5 are received with the printed or coated surface thereof uppermost by the conveyor 7 for carrying said sheets to the drying oven 6. This conveyor 7 includes a roller 21 and a plurality of tapes or belts 22 passing around and driven by said roller (Figs. 1 and 2). The roller 21 extends transversely of the machine 5 and is journaled in suitable bearings in the side frames 8 thereof. The front portions of the tapes or belts 22 pass around and drive a roller 23 which extends transversely of the conveyor 7 and is journaled in suitable bearings in side frames 24 and 25 thereof. The side frames 24 and 25 of conveyor 7 are bolted or otherwise suitably secured to the machine foundation and connected together by tie bars 26, 27 and 28. Also passing around the roller 23 and driven thereby are a plurality of tapes or belts 29 which extend forwardly of said roller and pass around a roller 30. The roller 30 extends transversely of the conveyor 7 and is journaled in suitable bearings in the side frames 24 and 25 thereof. The roller 21 and tapes or belts 22 and 29 are driven by suitable gearing including a spur pinion 31 that is fixed on said roller. This spur pinion 31 meshes with an idler gear 32 which, in turn, meshes with and is driven by the spur gear 19 on the cylinder 10. The idler gear 32 is journaled in any suitable manner on the adjacent side frame 8 of the machine 5.

Each sheet received by the conveyor 7 and advanced thereby toward the drying oven 6 is, in accordance with the present invention, moved sidewise and straightened on said conveyor so that when the sheet is presented to the drying oven said sheet will be straight and a side edge portion thereof will be in a definite position for action of suction sheet forwarding means to be hereinafter described. This sidewise movement

and straightening of the sheet may be effected by any suitable means for this purpose, but as herein shown, is preferably effected by magnetic means of the general type disclosed in the United States Patent No. 2,228,913, granted January 14, 1941, to George A. Martin.

This magnetic means includes the permanent magnet rollers 33 (Fig. 2) secured in spaced relation on a non-magnetic shaft 34 which extends 10 transversely of the conveyor 7 and is disposed diagonally of the tapes or belts 29 beneath the upper reaches thereof. The permanent magnet rollers 33 project upwardly between the tapes or 15 belts 29 in approximately the same plane as the upper reaches thereof. The non-magnetic shaft 34 is journaled in suitable bearings in brackets 35 and 36 which are bolted or otherwise suitably secured to the tie bar 27 and side frame 25, respectively. The shaft 34 and magnetic rollers 20 33 are driven from the tape roller 23 and for this purpose, said tape roller has fixed thereon and driven thereby a pulley 37 around which passes a belt 38 that also passes around and drives a pulley 39. This pulley 39 is fixed on and drives a stub shaft 40 which, in turn, is connected with and drives the shaft 34 through the medium of a universal coupling 41. The stub shaft 40 is journaled in suitable bearings in the side frame 24 and in a bracket 42 which is bolted 25 or otherwise suitably secured to the tie bar 27.

It will thus appear that as each sheet is advanced along the conveyor 7 by the tapes or belts 29, the sheet will engage the upper surfaces of the rotating permanent magnet rollers 33 and 30 adhere to said rollers. Upon continued rotation of the rollers 33 and due to the angular arrangement of said rollers, the sheet adhering thereto will be moved forwardly and sidewise thereby until the side edge of the sheet engages a sheet 35 guide 43, thus straightening and properly positioning the sheet on the conveyor 7 for presentation to the drying oven 6. The sheet guide 43 extends along the conveyor 7 at one side thereof and parallel with the tapes or belts 29 and is 40 secured to and adjustable along the tie bars 26 and 28.

The drying oven 6 is of any suitable type and includes a conveyor comprised by a pair of transversely spaced chains 44 (Figs. 1 to 3) having 50 attached thereto a large number of racks or wickets 45 for supporting and conveying a supply of the printed or coated sheets standing on edge one behind another and usually slightly inclined through the drying oven 6. The chains 44 pass 55 around sprockets 46, 47 and 48 which are fixed on shafts 49, 50 and 51, respectively. The shafts 49, 50 and 51 extend transversely of the drying oven 6 and are journaled in suitable bearings on side frames 52 and 53 thereof. The chains 44 60 and racks or wickets 45 are usually driven continuously and at the proper speed relatively to the printing or coating machine 5 and in a manner such that for each cycle of operation of the printing or coating machine a rack or wicket 45 65 will be in proper position to receive a printed or coated sheet from the conveyor 7.

For this purpose, the shaft 18 of the printing or coating machine 5 has fixed thereon and driven thereby a bevel gear 54 (Fig. 1) which 70 meshes with and drives a similar gear 55 that is fixed on one end of a jack shaft 56 and serves to drive the same. This jack shaft 56 extends along one side of the machine 5 and the conveyor 7 and is journaled in suitable bearings on the adjacent frames 8 and 24 of said machine

and conveyor, respectively. The shaft 58 has fixed thereon and driven thereby a sprocket 57 (Figs. 1 and 2) around which passes a chain 58 that extends transversely of the conveyor 1 to the opposite side thereof and passes around a sprocket 59 to drive the same. This sprocket 59 is fixed on and drives a jack shaft 60 which extends along the drying oven 6 at one side thereof and is journalled in suitable bearings on the frames 52 and 28 of said oven and the conveyor 1, respectively.

Fixed on and driven by the jack shaft 60 are sprockets 61 and 62 around which pass chains 63 and 64 that extend upwardly and also pass around sprockets 65 and 66, respectively. These sprockets 65 and 66 are fixed on and drive stub shafts 67 and 68 which are journalled in suitable bearings on the side frame 52 of the drying oven 6. Secured to and driven by the stub shafts 67 and 68 are worms 69 and 70 which mesh with and drive worm gears 71 and 72 that are fixed on the shafts 49 and 50, respectively. It will thus appear that the chains 44 and racks or wickets 45 through the described driving connections therefor with the shaft 18 are driven at the proper speed and in proper timed relation with the printing or coating machine 5.

In the operation of the unit thus far described, the sheets discharged in succession from the printing or coating machine 5 are received with the printed or coated surface thereof uppermost by the conveyor 1 and advanced by said conveyor in like manner and in horizontal position to successive racks or wickets 45. As the sheets are advanced by the conveyor 1 toward the drying oven 6 they are moved sidewise against the sheet guide 43 by the rotating angularly disposed magnetic rollers 33 so that one edge of each sheet extends a predetermined distance beyond one side of the racks or wickets 45 for action of suction sheet forwarding means to be hereinafter described. Upon continued operation of the chains 44 and racks or wickets 45 the sheets are turned from a horizontal position to a vertical position and conveyed standing on edge and with the printed or coated surface thereof facing in the conveying direction through the drying oven 6.

In accordance with the present invention means are provided for forwarding and advancing the sheets laterally and while standing on edge from the racks or wickets 45 after said sheets have passed through the drying oven 6 and were dried therein, and for piling the forwarded and advanced sheets one upon another and with the printed or coated surface thereof uppermost. Said means are preferably mounted, constructed and operated as follows. Disposed at one side of the drying oven 6 and adjacent the front or delivery end thereof is a pile delivery or other sheet receiving means indicated broadly at 73 (Figs. 1, 3 and 4) having a frame comprised by pairs of spaced side members 74 and 75 which are bolted or otherwise suitably secured to the machine foundation. The side members 74 and 75 are connected together by a pile guiding apron or plate 76 and a cross member 77 which are bolted or otherwise suitably secured to said side members.

Fixed on and driven by the jack shaft 60 is a sprocket 78 (Fig. 4) around which passes a chain 79 that also passes around a sprocket 80 which is fixed on and drives a cam shaft 81. This cam shaft 81 extends along the drying oven 6 between the latter and the pile delivery 73 and is journalled in suitable bearings in brackets 82

which are bolted or otherwise suitably secured to the side frame 52 of said oven. Fixed on and driven by the cam shaft 81 is a cam 83 (Figs. 4 and 7) that engages a roller 84 journalled on the lower end of a lever 85 which is pivotally mounted intermediate its ends on a bracket 86 bolted or otherwise suitably secured to the side frame 52 of the drying oven 6. The roller 84 is maintained in engagement with the cam 83 by a pull spring 87 having one end connected with the lever 85 and the opposite end connected with one of the side members 75 of the pile delivery 73. The lever 85 is thus rocked by the cam 83 during rotation thereof to reciprocate a link 88 having one end pivotally connected with the upper end of said lever and its opposite end pivotally connected, as by a ball and socket connection 89, with the free end of an arm 90. This arm 90 is fixed on and rocks a vertical shaft 91 which is journalled in suitable bearings in a bracket 92 and inclined in conformity with the racks or wickets 45 of the drying oven 6. The bracket 92 is bolted or otherwise suitably secured to one of the side members 75 of the pile delivery 73.

Secured in any suitable manner on the upper end of the rock shaft 91 and rocked thereby is a suction sheet forwarding device indicated broadly at 93 adapted to engage and forward the sheets in succession laterally and while standing on edge from the racks or wickets 45 after said sheets have passed through the drying oven 6 and were dried therein. This suction sheet forwarding device 93 is rocked into and out of engagement with the sheets by the rock shaft 91 through the described operating connections for said rock shaft with the cam 83, and actuated preferably by pneumatic means as hereinafter described in a direction at right angles to the sheet engaging movement thereof to forward the sheets from the racks or wickets 45.

As shown more particularly in Figs. 3, 4 and 5 of the drawings, the suction sheet forwarding device 93 is comprised by a horizontally disposed cylinder 94 closed at one end by a head 95 which is held in position by machine screws 96 or the like. The head 95 fits over and is secured in any suitable manner to the rock shaft 91 and for this purpose said head is provided with a suitable bore 97 to receive said shaft. Slidably mounted in the cylinder 94 is a piston 98 having secured thereto or formed integrally therewith a piston stem 99 which projects outwardly beyond the open end of said cylinder. Fixed on the outwardly projecting end of the piston stem 99 is a small cross head 100 in which is clamped for vertical adjustment a main conduit 101. Secured to or formed integrally with the main conduit 101 on the upper and lower ends thereof are branch conduits 102 which extend rearwardly from said main conduit and at right angles to the piston stem 99. Fixed on the open ends of these conduits 102 are sheet engaging rubber suction cups 103 provided with ducts 104 in communication with said cups and with said conduits.

Each branch conduit 102 has secured therein and preferably in the open end thereof, a plug 105 provided with a restricted opening 106 in communication with said conduit and with the duct 104 in the suction cup 103. The restricted openings 106 in plugs 105 insure that sufficient vacuum will be created and maintained in the conduits 101 and 102 so that in the event a sheet is, for any reason, engaged by only one of the suction cups 103 the volume of air passing through the restricted opening 106 in plug 105

associated with the other suction cup would not be sufficient to destroy the vacuum in the conduits 101 and 102. Under these conditions the sheet would be gripped by the single suction cup 103 which is effective and forwarded from the rack or wicket 45 thereby.

The piston 98, piston stem 99, cross head 100 and parts carried thereby are actuated in the sheet forwarding direction by vacuum as hereinabove described, and in the opposite direction by a push spring 107 which is interposed between said piston and the cylinder head 95 interiorly of the cylinder 94. The spring 107 has one end thereof carried in a pocket 108 formed in and extending along the piston stem 99, and the opposite end is engaged over and guided by a pin 109 which is disposed interiorly of the cylinder 94 and secured in any suitable manner in the cylinder head 95. Movement of the piston 98 by the spring 107 is limited by a collar 110 which is bolted or otherwise suitably secured to the cylinder 94 interiorly thereof and engaged by said piston. The piston 98 and suction cups 103 are guided for right line reciprocation relative to the cylinder 94 by rollers 111 and 112 which are journalled at right angles to each other on the cross head 100. The rollers 111 extend in and travel along elongated slots 113 formed in side plates 114, and the rollers 112 engage the inner sides of said plates. The plates 114 are bolted or otherwise suitably secured to the cylinder 94 exteriorly thereof and connected together by pins 115 bolted or otherwise suitably secured to said plates.

Suitable means are provided for creating and breaking vacuum at predetermined intervals in the suction cups 103 and cylinder 94 of the sheet forwarding device 93 and as herein shown said means are preferably mounted on and comprised by the following instrumentalities. Bolted or otherwise suitably secured to the cross member 77 of the pile delivery 73 is an electric motor 116 (Fig. 3) connected with a suitable source of current and controlled for starting and stopping purposes by suitable switch means (not shown). Fixed on and driven by the armature shaft 117 of motor 116 is a sprocket 118 around which passes a chain 119 that also passes around a sprocket 120 that is fixed on and drives the shaft 121 of a vacuum pump 122. The vacuum pump 122 is bolted or otherwise suitably secured on a platform 123 which, in turn, is bolted or otherwise suitably secured to the cross member 77.

Connected with the vacuum side of the pump 122 is one end of a conduit 124 the opposite end of which is connected with a valve housing 125 (Fig. 6) through the medium of a flexible conduit 126. The valve housing 125 is bolted or otherwise suitably secured to the side frame 52 of the drying oven 6. The valve housing 125 has formed therein a conduit 127 which is connected with the flexible conduit 126 and opens into bores 128 and 129 that are formed in said housing at opposite sides of the conduit 127. Connected with the housing 125 and communicating with the bore 128 therein is one end of a flexible conduit 130 the opposite end of which is connected with the main conduit 101 of the sheet forwarding device 93. Slidably mounted in the bore 128 of housing 125 is a valve 131 which projects downwardly through the housing and is provided on the lower end thereof with a roller 132 journalled on a pin 133. The roller 132 engages a cam 134 which is fixed on and rotated by the cam shaft

5 81. The roller 132 is held in engagement with the cam 134 by a spring 135 interposed between the upper end of the valve 131 and a plate 136 which is bolted or otherwise suitably secured to the housing 125. It will thus appear that the valve 131 is spring operated in one direction and cam operated in the opposite direction to make and break vacuum in the conduits 101, 102 and the suction cups 103. Turning movement of the valve 131 in the bore 128 is prevented by a pin 137 which is secured in the lower end of said valve and projects into a slot 138 formed in the housing 125.

15 The valve 131 is provided with a reduced portion 139 and the valve housing 125 is provided in the bore 128 thereof with a chamber 140 formed by the upper and lower ends of spaced bushings 141, 142 and communicating with the conduit 127. The housing 125 is further provided in the bore 128 thereof with a second chamber 143 formed by the upper end of the bushing 142 and the lower end of a third bushing 144. The chamber 143 communicates with a relief port 145 formed in the housing 125 and opening outwardly to atmosphere through one side of said housing. It will thus appear that when the roller 132 of valve 131 is in the low part of cam 134 the valve 131 will be in the position thereof shown in Fig. 6 wherein it will be noted that the reduced portion 139 of the valve is in communication with the conduit 127, the chamber 140 and the flexible conduit 130. Under these conditions vacuum will be created in the suction cups 103 through the described connections therefor to cause the sheet engaged thereby to adhere to said cups. It will further appear that when the roller 132 of valve 131 is engaged by the high part of cam 134 upon continued rotation thereof, the valve 131 will be raised so that the reduced portion 139 thereof is moved out of communication with the chamber 140 and into communication with the chamber 143. Vacuum will thus be broken in the bore 128, and the suction cups 103 will be opened to atmosphere through the conduit 130, the chamber 143, and the relief port 145 to cause said suction cups to release the sheet.

25 Secured in the valve housing 125 at the side thereof opposite that carrying the flexible conduit 130 is a tubular fitting 146 which communicates with the bore 129 in said housing. Connected with the tubular fitting 146 is one end of a flexible conduit 147 the opposite end of which is connected with the cylinder 94 and communicates with the interior thereof through a port 55 148 (Fig. 5) formed in said cylinder at one side thereof and adjacent the cylinder head 95. The tubular fitting 146 has also connected therewith one end of a flexible conduit 149 the opposite end of which is connected with a conduit 150 that is formed in the head 95 of cylinder 94. The conduit 150 communicates with a conduit 151 at the end of the cylinder 94. The illustrated construction shows the conduit 151 formed in the cylinder head 95 and disposed at right angles to the port 148 in cylinder 94. This conduit 151 opens into the interior of cylinder 94 and has secured in the open end thereof a plug 152 provided with a restricted opening 153 for purposes hereinafter described.

35 70 Slidably mounted in the bore 129 of valve housing 125 is a valve 154 (Fig. 6) which projects downwardly through the housing and is provided on the lower end thereof with a roller 155 journalled on a pin 156. The roller 155 engages a cam 157 which is fixed on and rotated

by the cam shaft 81. The roller 155 is held in engagement with the cam 157 by a spring 158 interposed between the plate 136 and the upper end of the valve 154. It will thus appear that the valve 154 is spring operated in one direction and cam operated in the opposite direction to make and break vacuum in the cylinder 94 of the sheet forwarding device 93. Turning movement of the valve 154 in the bore 129 is prevented by a pin 159 which is secured in the lower end of said valve and projects into a slot 160 formed in the housing 125.

The valve 154 is provided with a reduced portion 161 and the valve housing 125 is provided in the bore 129 thereof with a chamber 162 formed by the upper and lower ends of spaced bushings 163, 164 and communicating with the conduit 127 in said housing. The housing 125 is further provided in the bore 129 thereof with a second chamber 165 formed by the upper end of the bushing 164 and the lower end of a third bushing 166. The chamber 165 communicates with a relief port 167 formed in the housing 125 and opening outwardly to atmosphere through the same side of said housing as the relief port 145. It will thus appear that when the roller 155 is engaged with the low part of cam 157 during rotation thereof, the valve 154 will be lowered by the expanding action of spring 158 and thus establish communication between the conduit 127 and the tubular fitting 146 through the chamber 162 and the reduced portion 161 of said valve. Under these conditions vacuum will be created in the cylinder 94 through the flexible conduits 147, 148, the port 148, the conduits 150, 151 and the restricted opening 153.

When vacuum is created in the cylinder 94 as aforesaid, atmospheric air pressure through the open end of said cylinder acts on the piston 98 and pushes said piston, the piston stem 99, the cross head 100, the suction cups 103, and the sheet gripped by said suction cups rapidly toward the right (Fig. 5), compressing the spring 107. As the piston 98 approaches the cylinder head 95 the port 148 will be closed by said piston at which time vacuum will be created in the cylinder 94 only through the restricted opening 153. Under these conditions the piston 98 upon continued movement thereof by momentum toward the right (Fig. 5) will gradually build up a pressure of air between it and the cylinder head 95 due to the location of the port 148 relatively close to said cylinder head. However, since air is being continuously exhausted from the cylinder 94 through the restricted opening 153, said air pressure between the piston 98 and cylinder head 95 will never equal the atmospheric air pressure on the opposite side of the piston with the result that said piston will first slow down, whereupon vacuum created in said cylinder through said restricted opening causes the piston to gradually move into engagement with the cylinder head 95. In this manner knocking or pounding of the piston 98 against the cylinder head 95 which would result in possible damage to various elements of the sheet forwarding device 93 and also possible displacement of the sheet on the suction cups 103 is eliminated.

Upon continued rotation of the cam 157, the valve 154 will be raised by the high part of said cam to the position thereof shown in Fig. 6 thus establishing communication between the tubular fitting 146 and the relief port 167 through the chamber 165 and reduced portion 161 of said valve. Under these conditions vacuum will be

broken in the bore 129 of housing 125, and the cylinder 94 will be opened to atmosphere to release the piston 98 at which time the spring 107 through expansion thereof will return said piston and the suction cups 103 to their normal full line positions shown in Fig. 5 determined by engagement of the piston with the collar 110 in said cylinder.

The operations of the sheet forwarding device 93 are so timed relative to the printing or coating machine 5 and the travel of the sheets through the drying oven 6 that as the sheets arrive standing on edge at the proper feeding position, the sheet forwarding device 93 is rocked rearwardly by the rock shaft 91 to engage the suction cups 103 with the face of the leading sheet on its printed or coated surface and adjacent the side edge thereof. During this rearward movement of the sheet forwarding device 93 vacuum is created in the suction cups 103 by the described valve means (Fig. 6) for this purpose causing said cups to grip the sheet engaged thereby. At this time vacuum is created in the cylinder 94 by the described valve means (Fig. 6) for this purpose, whereupon the piston 98 moves to the right to the dotted line position thereof shown in Fig. 5 of the drawings. The suction cups 103 are moved with the piston, and the sheet gripped by said cups is forwarded laterally, and while standing on edge, a short distance from the rack or wicket 45 of the drying oven 6 to sheet advancing means to be herein-after described. The suction cups 103 are then released from the forwarded sheet by breaking of vacuum in said cups through the described valve means for this purpose, whereupon the sheet forwarding device 93 is rocked forwardly by the rock shaft 91 to move the suction cups 103 clear of the forwarded sheet. Vacuum is then broken in the cylinder 94 through the described valve means for this purpose at which time the piston 98 and the suction cups 103 are returned by the expanding action of the spring 107 to their original or extended positions to act on the next sheet which in the meantime has reached the proper feeding position. The above operations of the sheet forwarding device 93 are repeated in the order described so that the sheets are forwarded in succession automatically and laterally from successive racks or wickets 45 of the drying oven 6.

Each sheet forwarded laterally and in standing position from the racks or wickets 45 of the drying oven 6 by the sheet forwarding device 93 is delivered thereby to sheet advancing means which advance each sheet in like manner toward another mechanism such as the pile delivery 73. As herein shown, said sheet advancing means are preferably mounted, constructed and operated as follows. Connected with the driven pump shaft 121, as by a coupling 168, is a shaft 169 (Fig. 3) which extends transversely of the pile delivery 73 and is journaled at one end in a suitable bearing in one of the side members 74 of said delivery. Fixed on and rotated by the shaft 169 is a pulley 170 around which passes a belt 171 that also passes around a pulley 172 which is fixed on a shaft 173 and serves to drive the same. This shaft 173 extends transversely of the pile delivery 73 and is journaled in suitable bearings in the side members 74 and 75 thereof.

The shaft 173 has fixed thereon and driven thereby a bevel gear 174 (Fig. 4) which meshes with and drives a similar gear 175 that is fixed

on one end of a jack shaft 176 and serves to drive the same. This jack shaft 176 extends along one side of the pile delivery 73 between the latter and the drying oven 6 and is journaled in suitable bearings in brackets 177 and 178 that are bolted or otherwise suitably secured to the adjacent side member 75 of said delivery. Fixed on the opposite end of the jack shaft 176 and driven thereby is a bevel gear 179 which meshes with and drives a similar gear 180 that is fixed on and drives a stub shaft 181 journaled in a suitable bearing in the bracket 178. The stub shaft 181 is connected, as by a universal coupling 182, with the lower end of a vertical shaft 183 the upper end of which is connected as by a universal coupling 184, with a stub shaft 185. This stub shaft 185 is journaled in suitable bearings formed in angularly disposed plates 186 and 187 (Figs. 4 and 8) which extend over a frame 188 that is bolted or otherwise suitably secured to the side members 75 of the pile delivery 73.

The plates 186 and 187 are adjustably secured to plates 189 and 190, respectively, by bolts 191 which pass through slots 192 formed in the plates 187 and 189 and are threaded in suitable openings in the plates 186 and 190. The plates 189 and 190 have formed therein suitable openings to receive the upper ends of transversely spaced vertical shafts 193 and 194, respectively, which are journaled in suitable bearings in brackets 195 and 196 and inclined in conformity with the racks or wickets 45 of the drying oven 6 (Figs. 4, 8 and 9). The brackets 196 are bolted or otherwise suitably secured to the frame 188, and the brackets 195 are bolted or otherwise suitably secured to a bar 197 which is adjustably mounted on said frame for purposes hereinafter described.

Fixed on and driven by the stub shaft 185 is a pulley 198 provided with suitable grooves for the reception of two belts 199 and 200 which pass around said pulley and also around pulleys 201 and 202, respectively, that are fixed on the vertical shafts 193, 194 and serve to drive the same. The belts 199 and 200 may be tightened as desired, by loosening the bolts 191 and sliding the plates 186 and 187 relative to the plates 189 and 190. The vertical driven shafts 193 and 194 are made of non-magnetic material and have secured thereon a series of permanent magnet feed rollers 203 and 204, respectively (Figs. 3, 4 and 9). These permanent magnet feed rollers 203 and 204 are identical in construction as the permanent magnet rollers disclosed in the United States Patent No. 2,228,913 above referred to, and need no detail description herein. It might be mentioned, however, that the metal sheets forwarded into engagement with the permanent magnet feed rollers 203 and 204 will be attracted and adhere to said rollers through the application of magnetic forces applied to the non-printed or uncoated sides of the sheets at spaced points vertically across the same.

Arranged between the permanent magnet feed rollers 203 and 204 are overlapping plates 205 and 206 which bridge the space between said rollers and serve to guide the sheets from the rollers 203 to the rollers 204. The plate 205 is secured in any suitable manner to brackets 207 which, in turn, are bolted or otherwise suitably secured to and adjustable with the bar 197, and the plate 206 is secured in any suitable manner to brackets 208 which, in turn, are bolted or otherwise suitably secured to the frame 188. Bolted or otherwise

suitably secured to one of the side members 75 of the pile delivery 73 is a bracket 209 having secured thereto in any suitable manner a trough 210 which serves to support the sheets in standing position during movement imparted thereto by the permanent magnet feed rollers 203 and 204.

It will thus appear that each metal sheet forwarded laterally and in standing position from the racks or wickets 45 by the sheet forwarding device 93 is delivered thereby in like manner over the vertically disposed rotating permanent magnet feed rollers 203 which magnetically attract the sheet to said rollers. Upon continued rotation of the rollers 203, the sheet adhering thereto will be advanced thereby laterally and in standing position over the plates 205, 206 and along the trough 210 into engagement with the permanent magnet feed rollers 204 which further advance the sheet laterally and in standing position toward the pile delivery 73.

To enable handling of the various widths of sheets that may be conveyed through the drying oven 6, and to insure proper delivery of the sheets to the permanent magnet feed rollers 203 by the sheet forwarding device 93, the rollers 203 may be adjusted toward and away from the racks or wickets 45 and the sheets supported standing on edge thereby. This adjustment of the permanent magnet rollers 203 may be made while said rollers are in operation, thus avoiding stopping of the drying oven conveyor and movement of the sheets through the drying oven. Accordingly, the bar 197 has secured thereto spaced rack bars 211 (Figs. 4 and 9) which are slidably mounted in the frame 188. Journaled in suitable bearings in the frame 188 is a vertical shaft 212 having spur pinions 213 fixed thereon and rotated thereby, each of which pinion meshes with the teeth of a rack bar 211. Rotation is imparted to the shaft 212 and pinion 213 by a hand wheel 214 which is secured on the upper end of said shaft. It will thus appear that by rotating the hand wheel 214 and shaft 212, the permanent magnet feed rollers 203 and the sheet guiding plate 205 may be moved toward or away from the racks or wickets 45, as indicated in full and dotted lines in Fig. 9, through motion imparted to the bar 197 by engagement of the pinions 213 with the rack bars 211.

It will further appear that when the permanent magnet feed rollers 203 are adjusted as aforesaid, corresponding movement will be imparted to the vertical driven shaft 183 and the driving connections between said shaft and the shafts 193, 194 so that the permanent magnet feed rollers 203 and 204 are continuously connected with and driven by the shaft 183 regardless of the position of the rollers 203.

The sheets moved successively into engagement with the permanent magnet feed rollers 204 are advanced by said rollers laterally and in standing position along a sheet supporting and guiding device indicated broadly at 215, and into engagement with a sheet deflecting member 216 which is disposed at an angle in the path of movement of the sheets on said device (Figs. 3 and 9). The sheet supporting and guiding device 215 extends transversely of the pile delivery 73 above the pile apron or plate 76 thereof (Figs. 12 to 14 inclusive), and is comprised by a bar 217 (Fig. 11) having three equally spaced, radially disposed transversely extending blades 218 each provided on the outer extremity thereof with a shoulder 219. The shoulders 219 prevent forward displacement of the sheets dur-

ing movement of the same along the bar 217. The blades 218 form therebetween three transversely extending sheet supporting and guiding troughs 220 which are moved successively into sheet supporting and guiding position when the bar 217 is rotated for purposes hereinafter described. Accordingly, the bar 217 is journalled at one end thereof in a suitable bearing in the frame 188 (Fig. 9), and the opposite end of said bar is connected with a coupling 221 provided with three radially disposed grooves 222 into which the blades 218 extend (Figs. 10 and 11). The coupling 221 is, in turn, secured to a short shaft 223 which extends through and is journalled in a bushing 224 that is bolted or otherwise suitably secured to one of the side members 74 of the pile delivery 73. In the normal position of the bar 217 one of the troughs 220 is disposed in line with the trough 210, and one of the blades 218 is disposed in vertical alignment with the pile guiding apron or plate 76 as shown in Figs. 12 and 14 of the drawings.

The sheet deflecting member 216 is bolted or otherwise suitably secured above and in spaced relation with the sheet supporting and guiding device 215 to a side sheet piling guide 225 (Figs. 3 and 9) which, in turn, is bolted or otherwise suitably secured to a bar 228. The bar 226 is adjustably secured in a bracket 227 to provide for adjustment of the sheet piling guide 225 and the sheet deflecting member 216 toward and away from the permanent magnet feed rollers 204 in accordance with the size of sheet being handled. The bracket 227 is disposed between the side members 74 of the pile delivery 73 and bolted or otherwise suitably secured to said members.

Disposed in line with the permanent magnet feed rollers 204 and extending rearwardly therefrom is a side sheet piling guide 228 which is bolted or otherwise suitably secured to one of the side members 75 of the pile delivery 73. Disposed between the side sheet piling guides 225, 228 and at the rear of the pile delivery 73 is an end sheet piling guide 229 having a forwardly curved upper portion 230 (Fig. 4). The end sheet piling guide 229 is mounted for longitudinal and transverse adjustment to accommodate various sheet sizes, and for this purpose, said guide is bolted or otherwise suitably secured to a bar 231 that is adjustably secured in a bracket 232 which, in turn, is secured to and adjustable along a rear cross bar 233. The rear cross bar 233 is bolted or otherwise suitably secured to the side members 74 and 75 of the pile delivery 73.

It will thus appear as each sheet is advanced laterally and in standing or on edge position along one of the troughs 220 of the sheet supporting and guiding device 215 by the permanent magnet feed rollers 204, the upper end of the leading edge of the sheet will engage and move along the angularly disposed sheet deflecting member 216. Under these conditions, a transverse portion of the advancing sheet will be deflected rearwardly under tension out of alignment with the feed rollers 204 so that when said sheet is completely advanced by said rollers it will straighten out and thus cause the trailing end portion thereof to spring rearwardly out of engagement with the feed rollers 204. Thereupon, the entire sheet pivots on its lower edge and falls by gravity rearwardly and downwardly between the side guides 225, 228 and along the curved end guide 229 to a horizontal or flatwise position in the pile delivery 73 and with the 75

printed or coated surface of the sheet uppermost. When the sheet falls downwardly by gravity as aforesaid, air beneath the sheet is partly trapped by the guides 225, 228 and 229 causing said sheet to fall slowly to proper piling position in the pile delivery 73. At the same time, the sheet is held against rearward sliding movement by the curved end guide 229.

As soon as the advanced sheet starts to fall 10 rearwardly by gravity as hereinbefore described and as shown in Fig. 12 of the drawings, the bar 217 of the sheet supporting and guiding device 215 is rapidly rotated counterclockwise as viewed in Figs. 11 to 14 inclusive, a third of a revolution or one hundred and twenty degrees. This rotation of the bar 217 is necessary in order to insure complete delivery of the advanced sheet into the pile delivery 73 and thereby provide a free path for movement of the next sheet along said bar. When the bar 217 is rotated in the manner above stated, the lower edge of the rearwardly falling sheet will slide out of the trough 220 and into engagement with the adjacent blade 218 as indicated in full lines in Figs. 13 and 14 15 of the drawings. Thereupon the sheet falls bodily in an inclined position along the vertical blade 218 and along the front pile guiding apron or plate 76 until the lower edge of the sheet engages the top of the pile as indicated in broken lines in Fig. 14. During this movement of the sheet the lower edge thereof is maintained in engagement with the vertical blade 218 and the pile guiding apron or plate 76 due to the inclination of the sheet and the air partly trapped beneath the same. Upon engagement of the lower edge of the sheet with the pile as aforesaid, said sheet pivots about said edge and falls flat on top of the pile without sliding on and scratching or marring the underlying sheet. It might be mentioned, at this time, that when the bar 217 is rotated to insure complete delivery of the advanced sheet as described, the following trough 220 is simultaneously and automatically moved into position to support and guide the next sheet.

As herein shown, rotation of the bar 217 in the manner previously described, is preferably effected and controlled as follows. Disposed between the side members 74 of pile delivery 73 and fixed on the driven shaft 173 for rotation 25 thereby, is a spur pinion 234 (Fig. 10) which meshes with and drives a spur gear 235. This spur gear 235 is fixed on and drives a short shaft 236 which extends through and is journalled in suitable bearings in the side members 74 of the pile delivery 73. The short shaft 236 has also 30 fixed thereon and driven thereby a sprocket 237 around which passes a chain 238 that also passes around and drives a sprocket 239 which is loosely mounted on the outwardly projecting end of the short shaft 236. This sprocket 239 has secured thereto or formed integrally therewith a cup shaped clutch member 240 which is also loosely mounted on the outwardly projecting end of the short shaft 236. The clutch member 240 has suitably connected therewith a pair of driving disks 241 which frictionally drive a series of similar driving disks 242 through the medium of leather disks 243 that are interposed between said disks. The driving disks 242 are suitably connected with the short shaft 236 to drive said shaft, and said disks, the leather disks 243 and the driving disks 241 are retained in frictional driving contact with each other by a spring 244 having one end engaging against a collar 245

on the shaft 223 and the opposite end engaging against the outermost driving disk 242.

It will thus appear that the construction thus far described provides a continuous or constant driving connection between the bar 217 of the sheet supporting and guiding device 215 and the driven shaft 173 through the friction clutch member 240 and the described connections between said shaft and said clutch member and between the latter and said bar. Mechanism is, therefore, provided to hold the bar 217 against rotation while a sheet is being advanced therewith, and to release said bar for rotation after the sheet has been completely advanced and begins to fall rearwardly as hereinbefore described. This mechanism is preferably mounted, constructed and operated as follows.

Fixed on and rotated by the cam shaft 81 is a cam 246 (Figs. 4 and 7) which engages a roller 247 that is journalled on the lower end of a lever 248. This lever 248 is pivotally mounted intermediate its ends on a bracket 249 which is bolted or otherwise suitably secured to the adjacent side frame 52 of the drying oven 6. Pivotally connected with the upper end of the lever 248 is one end of a connecting rod 250 which extends transversely of the pile delivery 73 to the opposite side thereof through suitable openings formed in the adjacent side members 75. The lever 248 is thus rocked by the cam 246 during rotation thereof to reciprocate the connecting rod 250.

The opposite end of the connecting rod 250 is pivotally connected with one arm 251 of a bell crank 252 (Figs. 1, 10 and 11) having another arm 253 projecting into the space between the adjacent side members 74 through a suitable opening formed in one of said side members. The bell crank 252 is pivotally mounted on a bracket 254 which is bolted or otherwise suitably secured to one of the adjacent side members 74. The arm 253 of bell crank 252 has pivotally connected therewith, as by a ball and socket connection 255, the lower end of a connecting rod 256 which extends upwardly between the side members 74. The upper end of the connecting rod 256 is pivotally connected with one arm 257 of a bell crank 258 having another arm indicated at 259. The bell crank 258 is disposed between the side members 74 and pivotally mounted, as at 260, on one of said side members.

The arm 259 of bell crank 258 has pivotally connected therewith one end of a connecting rod 261 which extends rearwardly between the side members 74 (Figs. 10 and 11). The opposite end of the connecting rod 261 is pivotally connected with an arm 262 that is fixed on a pin 263 which is journalled in a suitable bearing in one of the side members 74 and through which said pin projects. Fixed on the outwardly projecting end of the pin 263 is an arm 264 having a forked lower end in which is pivotally mounted, as at 265, a pawl 266 provided on the free end thereof with a beveled edge 267. This pawl 266 normally engages a collar 268 adjustably secured on a toggle breaking pin 269 which is slidably mounted in spaced blocks 270 and 271 that are bolted or otherwise suitably secured to the adjacent side member 74. A pull spring 272 having one end connected with the arm 264 and the opposite end connected with the block 270 holds the pawl 266 in the normal position thereof shown in Fig. 11, and said spring also serves to maintain the roller 247 in engagement with the cam 246 through the described connections between the lever 248 and

the arm 264. Excess sliding movement of the toggle breaking pin 269 toward the left (Fig. 11) is prevented by a collar 273 which is adjustably secured on said pin and adapted to engage the block 270.

The toggle breaking pin 269 is disposed in alignment with and adapted to engage a toggle pivot pin 274 which pivotally connects pairs of upper and lower toggle links 275 and 276, respectively, that are normally disposed in straightened position. The toggle links 276 are pivotally connected, as at 277, with the adjacent side member 74, and the toggle links 275 are, in turn, pivotally connected, as at 278, with a detent 279 which is pivotally mounted intermediate its opposite ends, as at 280, on the adjacent side member 74. This detent 279 extends over a disk 281 and normally engages one of three shoulders 282 that are formed in and equally spaced around the periphery of said disk. The disk 281 is fixed on the short shaft 223 and it will therefore be apparent that said shaft and the bar 217 of the sheet supporting and guiding device 215 will be normally held against rotation through engagement of the detent 279 with one of the shoulders 282 on said disk. This, however, will not affect the operation of the shaft 173 due to the slip clutch connection with the short shaft 223. Seated in a suitable recess formed in the upper side of the detent 279 rearwardly of the pivot 280 thereof is the lower end of a spring pressed pin 283 the upper end of which is guided in an eye bolt 284 secured in any suitable manner to the adjacent side member 74. This spring pressed pin 283 tends to hold the toggle links 275, 276 in normal straightened position, and also aids in lifting the detent 279 out of engagement with the disk 281 upon breaking of said toggle links. The spring 285 for pin 283 is mounted thereon between the eye bolt 284 and a shoulder 286 formed on said pin.

Fixed on the short shaft 223 is a disk 287 disposed between the sprocket 239 and the disk 281. This disk 287 is provided with three identical cam surfaces 288 formed in and equally spaced around the periphery thereof. The cam surfaces 288 are adapted to successively engage a roller 289 journalled on the upper end of an arm 290 which is pivotally mounted, as at 291, on the adjacent side member 74. Secured in the upper end of the arm 290 and disposed in alignment with the toggle pivot pin 274 is a toggle straightening member preferably in the form of a machine screw 292 threaded in said arm and locked in adjusted position by a lock nut 293. The roller 289 on arm 290 is maintained in engagement with the cam surfaces 288 by a pull spring 294 having one end connected with said arm and the opposite end connected in any suitable manner with the adjacent side member 74.

Assuming now that a sheet has been completely advanced laterally and in standing position along one of the troughs 220 in the bar 217 by the permanent magnet feed rollers 204, and that said advanced sheet has started to fall rearwardly toward the pile delivery 73, the high part of cam 246 upon continued rotation thereof then engages the roller 247 and rocks the lever 248 clockwise as viewed in Fig. 7. The pawl 266 and the toggle breaking pin 269 are, through the described connections therefor with the lever 248, thus moved toward the right (Fig. 11) until the pin 269 engages the toggle pin 274 and breaks the toggle comprised by the links 275 and 276. During this movement of pawl 266 and toggle

breaking pin 268 thereby, the beveled edge 267 on said pawl engages and rides up on the block 271 so that upon breaking of the toggle 275, 276 the pawl 266 is raised out of engagement with the collar 268 on the pin 269 and movement of the latter by said pawl is thus discontinued.

Breaking of the toggles 275, 276 raises the detent 279, aided by the spring pressed pin 283, out of engagement with the shoulder 282 on disk 281, thereby releasing the short shaft 223 for 10 rotation by the driven shaft 173 through the described driving connections between said shafts including the friction clutch 240. Thereupon the bar 217 of the sheet supporting and guiding device 215 is rotated one third of a revolution from the position thereof shown in Fig. 12 to the position thereof shown in Fig. 14, at which time said bar is again stopped through lowering of detent 279 and engagement of the same with the following shoulder 282 on disk 281. The advanced 20 sheet is thus completely removed from the bar 217 as hereinbefore described, and the following trough 220 is in position to support and guide the next sheet.

Lowering of detent 279 and stopping of the 25 bar 217 thereby is accomplished as follows. When the short shaft 223 and the bar 217 are rotated, as aforesaid, like movement is imparted to the disks 281 and 287 on said shaft, whereupon the high part of one of the cam surfaces 288 on disk 287 engages the roller 289 on arm 290 and rocks said arm counter clockwise as viewed in Fig. 11. The toggle straightening member 292 then strikes the toggle pin 274, thereby straightening the toggle 275, 276 and lowering the 30 detent 279 into the path of the following shoulder 282 on the disk 281. This occurs before the bar 217 has rotated one third of a revolution so that when said bar has reached the position thereof shown in Fig. 14 the following shoulder 282 on disk 281 engages the detent 279 thus 35 stopping the bar and holding same against further movement. At this time, the roller 289 on arm 290 engages the low part of the following cam surface 288 on disk 287 induced by the spring 294 returning said arm and the toggle straightening member 292 to their original positions. When the toggle 275, 276 is straightened, as 40 aforesaid, the toggle breaking pin 269 is moved thereby toward the left (Fig. 11) to its original position and the collar 268 on said pin is again engaged with the pawl 266 which, in the meantime, has returned to its original position through engagement of roller 247 on arm 248 with the 45 low part of cam 246 induced by the spring 272. The above described operations are repeated for each sheet advanced laterally and in standing position along the sheet supporting and guiding device 215 whereby successive sheets are properly delivered into the pile delivery 13 and piled evenly one upon another with the printed or coated surface thereof uppermost and without scratching or marring said sheets.

The pile delivery 13 as herein shown, is constructed and operated along the lines of deliveries known in the art and needing no detail description herein. It might be pointed out, however, that the pile delivery 13 includes, in addition to the side members 14, 15, the pile guiding apron or plate 78 and the cross member 11, a pile board or elevator 295 having connected therewith rear cables 296 (Fig. 4) which pass over sheaves (not shown) at the rear and top of the pile delivery 13. The pile board or elevator 295 also has connected therewith front cables 297 75

and these cables, as well as the cables 296 pass over sheaves 298 (Fig. 3) journalled in any suitable manner at the top and forward end of the pile delivery 13. The cables 296, 297 extend downwardly and are secured to and wound upon drums 299 which are located at opposite sides and near the bottom of the pile delivery 13. The drums 299 have secured thereto or formed integrally therewith worm gears 300 and these gears and the drums are fixed on stub shafts 301 which are journalled in suitable bearings in the cross member 11 and in brackets 302 that are bolted or otherwise suitably secured to said cross member.

Worm gears 300 mesh with and are driven by worms 303 which are fixed on opposite ends of a driven worm shaft 304 extending transversely of the pile delivery 13 and journalled in suitable bearings in brackets 305 that are bolted or otherwise suitably secured to the cross member 11. As the height of the pile on the board or elevator 295 increases, the worm shaft 304 is operated from time to time by suitable means (not shown) to drive worm gears 300 and drums 299 so that the cables 296, 297 are unwound from said drums and lower the pile board or elevator 295 and the pile of sheets thereon.

While the present invention is herein illustrated and described in association with a printing or coating machine and drying oven unit for metal sheets, it is equally adaptable for forwarding and advancing metal sheets laterally and in standing position from any supply of such sheets standing on edge one behind another, and delivering said sheets in horizontal or flatwise position to sheet receiving means for further handling thereof. It also will be apparent that constructional details of the present invention may be varied or modified without departing from the spirit of the invention whereby other sheets, as well as metal sheets, may be handled. For example, suction feed rollers or ordinary feed rollers and pressure rollers cooperating therewith may be employed instead of the permanent magnet feed rollers 203, 204, or pressure rollers may be employed with said permanent magnet feed rollers.

From the description of the machine given, it will now appear that means are provided, as in 50 the suction means 93 and the vertically mounted rollers 203 and 204, for removing the sheets from the wickets 45 and delivering the same to a position completely away from the wickets, that is, at the trough bar 217. In this position, 55 the sheets are ready for another handling of any suitable kind. Preferably, however, the trough bar and associated devices turn or deliver the sheets in a horizontal position and provide the means for this type of delivery of the sheets.

60 Any suitable means receives the horizontally positioned sheets which, in the embodiment illustrated, is the pile board or elevator 295.

It is therefore to be expressly understood that the present invention is not limited to the embodiment thereof herein illustrated and described or to the specific type of equipment disclosed or otherwise than by the terms of the appended claims.

What we claim is:

1. In apparatus for removing sheets from the type of conveying means which supports and conveys a supply of sheets standing on edge one behind another: the combination of means operable to remove the sheets in succession laterally and in standing position from said conveying

means; means arranged for engagement by the lower edges of the successive sheets to prevent downward edgewise displacement of said sheets during lateral movement thereof; means arranged to act on each removed sheet to cause it to turn from standing position to horizontal position; and means to receive the horizontally positioned sheets.

2. In apparatus for removing sheets printed or coated on one surface from the type of conveying means which supports and conveys a supply of said sheets standing on edge one behind another: the combination of means operable to remove the sheets in succession laterally and in standing position from said conveying means; means arranged for engagement by the lower edges of the successive sheets to prevent downward edgewise displacement of said sheets during lateral movement thereof; means arranged to act on each removed sheet to cause it to turn from standing position to horizontal position with the printed or coated surface thereof lying upwardly; and means to receive the horizontally positioned sheets.

3. In apparatus for removing sheets printed or coated on one surface from the type of conveying means which supports and conveys a supply of said sheets standing on edge one behind another and with the printed or coated surface facing in the conveying direction: the combination of means operable to remove the sheets in succession laterally and in standing position from said conveying means including suction means to engage the printed or coated surface of each sheet; means arranged for engagement by the lower edges of the successive sheets to prevent downward edgewise displacement of said sheets during lateral movement thereof; means arranged to act on each removed sheet to cause it to turn from standing position to horizontal position with the printed or coated surface thereof lying upwardly; and means to receive the horizontally positioned sheets.

4. In apparatus for removing sheets from the type of conveying means which supports and conveys a supply of sheets standing on edge one behind another: the combination of means operable to remove the sheets in succession laterally and in standing position from said conveying means; means for supporting the successive sheets in standing position during lateral movement thereof; means for operating said last named means at predetermined intervals to remove the successive sheets therefrom; and means for receiving the removed sheets.

5. In apparatus for removing sheets from the type of conveying means which supports and conveys a supply of sheets standing on edge one behind another; the combination of means operable to remove the sheets in succession laterally and in standing position from said conveying means including suction means to grip each sheet; means for supporting and guiding the successive sheets in standing position during lateral movement thereof, said last named means comprising a transversely extending member having a trough along which the successive sheets are laterally advanced; means for actuating said member at predetermined intervals to remove the successive sheets from the trough thereof; and means for receiving the removed sheets.

6. In apparatus for removing sheets from the type of conveying means which supports and

conveys a supply of sheets standing on edge one behind another: the combination of means operable to remove the sheets in succession laterally and in standing position from said conveying means; rotatable means for supporting the successive sheets in standing position during lateral movement thereof; means for rotating said last named means at predetermined intervals a portion of a revolution to remove the successive sheets therefrom; and means for receiving the removed sheets.

7. In apparatus for removing sheets from the type of conveying means which supports and conveys a supply of sheets standing on edge one behind another: the combination of means operable to remove the sheets in succession laterally and in standing position from said conveying means including suction means to grip each sheet; means for supporting and guiding the successive sheets in standing position during lateral movement thereof, said last named means comprising a transversely extending rotatable member having a plurality of troughs equally spaced around the same and along the upper trough of which the successive sheets are laterally advanced; means for rotating said member at predetermined intervals a portion of a revolution to remove each sheet from its respective trough and to dispose the following trough in position to support and guide the next sheet; and means for receiving the removed sheets.

8. In apparatus for removing sheets from the type of conveying means which supports and conveys a supply of sheets standing on edge one behind another: the combination of means operable to remove the sheets in succession laterally and in standing position from said conveying means including suction means to grip each sheet; means for supporting the successive sheets in standing position during lateral movement thereof; means for causing each removed sheet to fall rearwardly and downwardly to horizontal position; and means for receiving the horizontally positioned sheets.

9. In apparatus for removing sheets from the type of conveying means which supports and conveys a supply of sheets standing on edge one behind another: the combination of means operable to forward the sheets in succession laterally and in standing position from said conveying means; and means receiving the forwarded sheets and adapted to advance said sheets in like manner for further handling thereof.

10. In apparatus for removing sheets from the type of conveying means which supports and conveys a supply of sheet standing on edge one behind another: the combination of suction means operable to forward the sheets in succession laterally and in standing position from said conveying means; and driven rotatable means receiving the forwarded sheets and adapted to advance said sheets in like manner for further handling thereof.

11. In apparatus from the type of conveying means which supports and conveys a supply of said sheets standing on edge one behind another: the combination of suction means operable to forward the metal sheets in succession laterally and in standing position from said conveying means; and driven rotatable magnetic means receiving the forwarded metal sheets and adapted to advance said sheets in like manner for further handling thereof.

12. In apparatus for removing metal sheets from the type of conveying means which sup-

ports and conveys a supply of said sheets standing on edge one behind another: the combination of suction means operable to forward the metal sheets in succession laterally and in standing position from said conveying means; and driven rotatable permanent magnet means receiving the forwarded metal sheets and adapted to advance said sheets in like manner for further handling thereof.

13. In apparatus for removing sheets from the type of conveying means which supports and conveys a supply of sheets standing on edge one behind another: the combination of means operable to forward the sheets in succession laterally and in standing position from said conveying means; vertically disposed means receiving the forwarded sheets and adapted to advance said sheets further laterally and in standing position; and means for supporting and guiding the sheets in standing position during lateral movement imparted thereto by said last named means.

14. In apparatus for removing sheets from the type of conveying means which supports and conveys a supply of sheets standing on edge one behind another: the combination of suction means operable to forward the sheets in succession laterally and in standing position from said conveying means; vertically disposed driven rotatable means receiving the forwarded sheets and adapted to advance said sheets further laterally and in standing position; and means for supporting and guiding the sheets in standing position during lateral movement imparted thereto by said rotatable means.

15. In apparatus for removing metal sheets from the type of conveying means which supports and conveys a supply of said sheets standing on edge one behind another: the combination of suction means operable to forward the metal sheets in succession laterally and in standing position from said conveying means; vertically disposed driven rotatable magnetic means receiving the forwarded metal sheets and adapted to advance said sheets further laterally and in standing position; and means for supporting and guiding the metal sheets in standing position during lateral movement imparted thereto by said rotatable magnetic means.

16. In apparatus for removing metal sheets from the type of conveying means which supports and conveys a supply of said sheets standing on edge one behind another: the combination of suction means operable to forward the metal sheets in succession laterally and in standing position from said conveying means; vertically disposed driven rotatable permanent magnet means receiving the forwarded metal sheets and adapted to advance said sheets further laterally and in standing position; and means for supporting and guiding the metal sheets in standing position during lateral movement imparted thereto by said rotatable permanent magnet means.

17. In apparatus for removing sheets from the type of conveying means which supports and conveys a supply of sheets standing on edge one behind another: the combination of suction means mounted for movement rearwardly and laterally to engage and forward the sheets in succession laterally and in standing position from said conveying means; sheet advancing means adapted to receive and further advance the forwarded sheets; means for moving the suction means rearwardly; and other means for moving the suction means laterally.

18. In apparatus for removing sheets from the type of conveying means which supports and conveys a supply of sheets standing on edge one behind another: the combination of suction means movable rearwardly and laterally to engage and forward the sheets in succession laterally and in standing position from said conveying means; sheet advancing means receiving the sheets from said suction means and adapted to advance the sheets further laterally and in standing position; means for moving the suction means rearwardly; other means for moving the suction means laterally; and means for supporting and guiding the sheets in standing position during lateral movement imparted thereto by said sheet advancing means.

19. In apparatus for removing sheets from the type of conveying means which supports and conveys a supply of sheets standing on edge one behind another: the combination of suction means mounted for movement rearwardly and laterally to engage and forward the sheets in succession laterally and in standing position from said conveying means; sheet advancing means adapted to receive and further advance the forwarded sheets; means for mechanically moving the suction means rearwardly as aforesaid; and means for pneumatically moving the suction means laterally as aforesaid.

20. In apparatus for removing sheets from the type of conveying means which supports and conveys a supply of sheets standing on edge one behind another: the combination of vertically disposed sheet advancing means; suction means movable rearwardly and laterally in one direction to engage and forward each sheet laterally and in standing position from said conveying means to said sheet advancing means, and movable forwardly and laterally in the opposite direction to clear the forwarded sheet and return to position to act on the next sheet; and means for imparting said four movements to the suction means in the sequence named.

21. In apparatus for removing sheets from the type of conveying means which supports and conveys a supply of sheets standing on edge one behind another: the combination of vertically disposed sheet advancing means; suction means movable rearwardly and laterally in one direction to engage and forward each sheet laterally and in standing position from said conveying means to said sheet advancing means, and movable forwardly and laterally in the opposite direction to clear the forwarded sheet and return to position to act on the next sheet; means for mechanically actuating the suction means rearwardly and forwardly as aforesaid; means for pneumatically actuating the suction means laterally in said first named direction; and means for mechanically actuating the suction means laterally in said last named direction.

22. In apparatus for removing sheets from the type of conveying means which supports and conveys a supply of sheets standing on edge one behind another: the combination of vertically disposed sheet advancing means; sheet forwarding means operable to forward the sheets in succession laterally and in standing position from said conveying means to said sheet advancing means, said sheet forwarding means comprising a horizontally disposed and transversely extending cylinder, a piston in said cylinder, and suction sheet engaging means connected with the piston and disposed at right angles thereto; means for actuating the cylinder

der and the suction sheet engaging means as a unit to engage said suction means with the leading sheet of the supply; and means for actuating the piston and the suction sheet engaging means relative to the cylinder to forward the sheet engaged by said suction means.

23. In apparatus for removing sheets from the type of conveying means which supports and conveys a supply of sheets standing on edge one behind another: the combination of vertically disposed sheet advancing means; sheet forwarding means operable to forward the sheets in succession laterally and in standing position from said conveying means to said sheet advancing means, said sheet forwarding means comprising a horizontally disposed and transversely extending cylinder, a piston in said cylinder, and suction sheet engaging means connected with the piston and disposed at right angles thereto; means for mechanically actuating the cylinder and the suction sheet engaging means as a unit to engage said suction means with the leading sheet of the supply; means for creating vacuum in the cylinder to actuate the piston and the suction sheet engaging means relative to the cylinder to forward the sheet engaged by said suction means; and automatically operated valve means for controlling the making and breaking of vacuum in the suction sheet engaging means and the cylinder at predetermined intervals and in proper timed relation with each other.

24. In apparatus for removing sheets from the type of conveying means which supports and conveys a supply of sheets standing on edge one behind another: the combination of vertically disposed rotatable sheet advancing means; sheet forwarding means operable to forward the sheets in succession laterally and in standing position from said conveying means to said sheet advancing means, said sheet forwarding means comprising a horizontally disposed and transversely extending cylinder, a piston in said cylinder, and suction sheet engaging means connected with the piston and disposed at right angles thereto; means for mechanically actuating the cylinder and the suction sheet engaging means as a unit to engage said suction means with the leading sheet of the supply; and means for creating vacuum in the cylinder whereby the piston and the suction sheet engaging means are actuated first rapidly and then slowly to forward the sheet engaged by said suction sheet engaging means.

25. Mechanism for forwarding sheets successively from a supply thereof and comprising: a horizontally disposed cylinder; a piston in said cylinder; suction sheet engaging means connected with said piston and disposed at right angles thereto; means for actuating the cylinder and the suction sheet engaging means as a unit to engage the latter with the sheets; and means for actuating the piston and the suction sheet engaging means horizontally relative to the cylinder to forward in succession the sheets engaged by said suction means.

26. Mechanism for forwarding sheets successively from a supply thereof and comprising: a horizontally disposed cylinder; a piston in said cylinder; suction sheet engaging means connected with said piston and disposed at right angles thereto; means for mechanically actuating the cylinder and the suction sheet engaging means as a unit to engage the latter with the sheets; and means for pneumatically actuating the piston and the suction sheet engaging means hori-

zontally relative to the cylinder to forward in succession the sheets engaged by said suction means.

27. Mechanism for forwarding sheets successively from a supply thereof and comprising: a horizontally disposed cylinder; a piston in said cylinder; suction sheet engaging means connected with said piston and disposed at right angles thereto; means for mechanically actuating the cylinder and the suction sheet engaging means as a unit to engage the latter with the sheets; means for creating vacuum in the cylinder to actuate the piston and the suction sheet engaging means horizontally in one direction relative to said cylinder to forward in succession the sheets engaged by said suction means; means for actuating the piston and the suction sheet engaging means horizontally in the opposite direction relative to the cylinder; and automatically operated valve means for making and breaking vacuum in the suction sheet engaging means and the cylinder in proper timed relation with each other.

28. Mechanism for forwarding sheets successively from a supply thereof and comprising: a pivotally mounted horizontally disposed cylinder; a piston in said cylinder; suction sheet engaging means connected with said piston and disposed at right angles thereto; means for oscillating the cylinder and the suction sheet engaging means as a unit to engage the latter with the sheets, a pump connected with the suction sheet engaging means and the cylinder to create vacuum therein and actuate the piston and said suction means horizontally relative to said cylinder to forward the sheets; and automatically operated valve means for connecting said pump with and disconnecting the same from said suction sheet engaging means and said cylinder at predetermined intervals and in proper timed relation with each other.

29. Mechanism for forwarding sheets successively from a supply thereof and comprising: a horizontally disposed cylinder; a piston reciprocable in said cylinder and having a piston stem extending through one end thereof; a cross head secured to said piston stem exteriorly of the cylinder; suction sheet engaging means carried by said cross head and disposed at right angles to said piston stem; and means on the cylinder and cross head guiding the piston and suction sheet engaging means for right line reciprocation thereof relative to said cylinder.

30. Mechanism for forwarding sheets successively from a supply thereof and comprising: a horizontally disposed cylinder; a piston in said cylinder; suction sheet engaging means connected with the piston and disposed at right angles thereto; and means for creating vacuum in the cylinder whereby the piston and the suction sheet engaging means are first rapidly and then slowly actuated relative to said cylinder to forward in succession the sheets engaged by said suction means.

31. Mechanism for forwarding sheets successively from a supply thereof and comprising: a horizontally disposed cylinder having a port therein at one side and spaced from one end thereof, and a second port at said end, said second named port being smaller in diameter than said first named port; a piston slidably mounted in said cylinder and adapted during movement thereof to close said first named port; suction sheet engaging means connected with the piston and disposed at right angles thereto; means for

creating vacuum in said cylinder through said first and second named ports whereby the piston and the suction sheet engaging means are first rapidly actuated relative to said cylinder until said piston closes said first named port and then slowly actuated for the remainder of their movements to forward in succession the sheets engaged by said suction means from the supply without pounding or knocking of the piston in the cylinder.

32. A suction sheet handling device comprising: a main conduit connected with a source of vacuum; a plurality of branch conduits connected with said main conduit and extending therefrom at right angles thereto; suction sheet engaging cups secured to the open free ends of said branch conduits; and an element secured in each branch conduit and provided with a restricted opening through which vacuum is created in each suction cup and whereby vacuum is maintained in the main and branch conduits.

33. In apparatus for removing sheets from the type of conveying means which supports and conveys a supply of sheets standing on edge one behind another: the combination of means operable to forward the sheets in succession laterally and in standing position from said conveying means; vertically disposed driven rotatable means receiving the forwarded sheets and adapted to advance said sheets further laterally and in standing position; means for supporting the sheets in standing position during lateral movement imparted thereto by said rotatable means; and means for operating said last named means at predetermined intervals to remove the advanced sheets therefrom.

34. In apparatus for removing metal sheets from the type of conveying means which supports and conveys a supply of said sheets standing on edge one behind another: the combination of suction means operable to forward the metal sheets in succession laterally and in standing position from said conveying means; vertically disposed driven magnetic feed rollers receiving the forwarded metal sheets and adapted to advance said sheets further laterally and in standing position; rotatable means for supporting the metal sheets in standing position during lateral movement imparted thereto by said magnetic feed rollers; and means for rotating said rotatable means at predetermined intervals a portion of a revolution to remove the advanced metal sheets therefrom.

35. In apparatus for removing sheets from the type of conveying means which supports and conveys a supply of sheets standing on edge one behind another: the combination of means operable to forward the sheets in succession laterally and in standing position from said conveying means; vertically disposed driven rotatable means receiving the forwarded sheets and adapted to advance said sheets further laterally and in standing position; means for supporting and guiding the sheets in standing position during lateral movement imparted thereto by said rotatable means; means for moving the upper transverse portion of each sheet advanced by said rotatable means out of alignment therewith and causing said sheet to fall downwardly to horizontal or flatwise position; and means for receiving in succession the sheets in horizontal or flatwise position.

36. In apparatus for removing sheets from the type of conveying means which supports and conveys a supply of sheets standing on edge one

7 behind another: the combination of means operable to forward the sheets in succession laterally and in standing position from said conveying means; vertically disposed driven rotatable means receiving the forwarded sheets and adapted to advance said sheets further laterally and in standing position; means for supporting and guiding the sheets in standing position during lateral movement imparted thereto by said rotatable means; means disposed angularly across the path of movement of each sheet advanced by said rotatable means for moving the upper transverse portion of the sheet out of alignment with said rotatable means and causing the sheet to fall downwardly to horizontal or flatwise position; and means for receiving in succession the sheets in horizontal or flatwise position.

37. In apparatus for removing sheets from the type of conveying means which supports and conveys a supply of sheets standing on edge one behind another: the combination of suction means operable to forward the sheets in succession laterally and in standing position from said conveying means; vertically disposed driven feed rollers receiving the forwarded sheets and adapted to advance said sheets further laterally and in standing position; a device for supporting and guiding the sheets in standing position during lateral movement imparted thereto by said feed rollers; means for moving the upper transverse portion of each sheet advanced by said feed rollers rearwardly out of alignment therewith and causing said sheet to fall rearwardly and downwardly to horizontal or flatwise position; and means for receiving in succession the sheets in horizontal or flatwise position.

38. In apparatus for removing metal sheets from the type of conveying means which supports and conveys a supply of said sheets standing on edge one behind another: the combination of suction means operable to forward the metal sheets in succession laterally and in standing position from said conveying means; vertically disposed driven magnetic feed rollers receiving the forwarded metal sheets and adapted to advance said sheets further laterally and in standing position; a device for supporting and guiding the metal sheets in standing position during lateral movement imparted thereto by said magnetic feed rollers; a member disposed angularly across the path of movement of each metal sheet advanced by said magnetic feed rollers for deflecting the upper transverse portion of the sheet rearwardly out of alignment with said magnetic feed rollers and causing the sheet to fall rearwardly and downwardly to horizontal or flatwise position; and means for receiving in succession the metal sheets in horizontal or flatwise position.

39. In apparatus for removing sheets from the type of conveying means which supports and conveys a supply of sheets standing on edge one behind another: the combination of means operable to forward the sheets in succession laterally and in standing position from said conveying means; vertically disposed driven rotatable means receiving the forwarded sheets and adapted to advance said sheets further laterally and in standing position; means for supporting and guiding the sheets in standing position during lateral movement imparted thereto by said rotatable means, said sheet supporting and guiding means comprising a transversely extending member having a trough along which the sheets are advanced by said rotatable means; means for moving the up-

per transverse portion of the sheets advanced by the rotatable means out of alinement therewith and causing said sheets to fall downwardly to horizontal or flatwise position; means for actuating said member at predetermined intervals to remove the advanced sheets from the trough thereof; and means for receiving in succession the sheets in horizontal or flatwise position.

40. In apparatus for removing sheets from the type of conveying means which supports and conveys a supply of sheets standing on edge one behind another: the combination of means operable to forward the sheets in succession laterally and in standing position from said conveying means; vertically disposed driven rotatable means receiving the forwarded sheets and adapted to advance said sheets further laterally and in standing position; means for supporting and guiding the sheets in standing position during lateral movement imparted thereto by said rotatable means, said sheet supporting and guiding means comprising a transversely extending rotatable member having a plurality of troughs equally spaced around the same and along the upper trough of which the sheets are advanced in succession by said rotatable means; means for moving the upper transverse portion of each sheet advanced by the rotatable means out of alinement therewith and causing said sheet to fall downwardly to a horizontal or flatwise position; means for rotating said member at predetermined intervals a portion of a revolution to remove the advanced sheet from its respective trough and to dispose the following trough in position to support and guide the next sheet; and means for receiving in succession the sheets in horizontal or flatwise position.

41. In apparatus for removing metal sheets from the type of conveying means which supports and conveys a supply of said sheets standing on edge one behind another: the combination of suction means operable to forward the metal sheets in succession laterally and in standing position from said conveying means; vertically disposed driven magnetic feed rollers receiving the forwarded metal sheets and adapted to advance said sheets further laterally and in standing position; a transversely extending device provided with a trough for supporting and guiding the metal sheets in standing position during lateral movement imparted thereto by said magnetic feed rollers; a member disposed angularly across the path of movement of each metal sheet advanced by said magnetic feed rollers for deflecting the upper transverse portion of said sheet rearwardly out of alinement with said magnetic feed rollers and causing the sheet to fall rearwardly and downwardly to horizontal or flatwise position; means for actuating said device at predetermined intervals to remove the advanced sheets from the trough thereof; and means for receiving in succession the metal sheets in horizontal or flatwise position.

42. In apparatus for removing metal sheets from the type of conveying means which supports and conveys a supply of said sheets standing on edge one behind another: the combination of suction means operable to forward the metal sheets in succession laterally and in standing position from said conveying means; vertically disposed driven magnetic feed rollers receiving the forwarded metal sheets and adapted to advance said sheets further laterally and in standing position; a transversely extending rotatable device provided with three troughs equally spaced

around the same for successively supporting and guiding successive metal sheets in standing position during lateral movement imparted thereto by said magnetic feed rollers; a member disposed angularly across the path of movement of each metal sheet advanced by said magnetic feed rollers for deflecting the upper transverse portion of said sheet rearwardly out of alinement with said magnetic feed rollers and causing the sheet to fall rearwardly and downwardly to horizontal or flatwise position; means for rotating said device at predetermined intervals a third of a revolution to remove the advanced metal sheet from its respective trough and to dispose the following trough in position to support and guide the next metal sheet; and means for receiving in succession the metal sheets in horizontal or flatwise position.

43. In apparatus for removing sheets printed or coated on one surface from the type of conveying means which supports and conveys a supply of said sheets standing on edge one behind another and with the printed or coated surface facing in the conveying direction: the combination of means operable to forward the sheets in succession laterally and in standing position from said conveying means through engagement of said sheets on the printed or coated surface thereof; vertically disposed driven rotatable means receiving the forwarded sheets and adapted to advance said sheets further laterally and in standing position through engagement of the same on the opposite side thereof; means for supporting and guiding the sheets in standing position during lateral movement imparted thereto by said rotatable means; means for moving the upper transverse portion of each sheet advanced by said rotatable means rearwardly out of alinement therewith and causing said sheet to fall rearwardly and downwardly to horizontal or flatwise position with the printed or coated surface thereof uppermost; and means for receiving the sheets in succession in horizontal or flatwise position and with the printed or coated surface thereof uppermost.

44. In apparatus for removing sheets from the type of conveying means which supports and conveys a supply of sheets standing on edge one behind another: the combination of sheet advancing means comprising vertically disposed driven rotatable means arranged at one side of and in spaced relation with said conveying means; sheet forwarding means operable to forward the sheets in succession laterally and in standing position from said conveying means and deliver said sheets to said rotatable means; and means providing for adjustment of the rotatable means toward and away from the conveying means to insure proper delivery of the sheets thereto by said sheet forwarding means.

45. In apparatus for removing metal sheets from the type of conveying means which supports and conveys a supply of said sheets standing on edge one behind another: the combination of sheet advancing means comprising a series of vertically disposed driven magnetic feed rollers arranged at one side of and in spaced relation with said conveying means; suction sheet forwarding means operable to forward the metal sheets in succession laterally and in standing position from said conveying means and bring said sheets into the magnetic influence of said feed rollers; and means providing for adjustment of the magnetic feed rollers toward and away from the conveying means to insure proper delivery

of the sheets thereto by said suction sheet forwarding means.

46. In apparatus for removing metal sheets from the type of conveying means which supports and conveys a supply of said sheets standing on edge one behind another: the combination of sheet advancing means comprising a series of vertically disposed magnetic feed rollers arranged at one side of and in spaced relation with said conveying means; means for continuously driving said series of magnetic feed rollers; suction sheet forwarding means operable to forward the metal sheets in succession laterally and in standing position from said conveying means and bring said sheets into the magnetic influence of said feed rollers; and means providing for adjustment of the magnetic feed rollers toward and away from the conveying means during rotation of said rollers and without disconnection of the driving means therefor to insure proper delivery of the metal sheets to the feed rollers by the suction sheet forwarding means.

47. In apparatus for removing sheets from the type of conveying means which receives sheets one after another at the rear thereof and supports and conveys a supply of the sheets standing on edge one behind another: the combina-

tion of sheet forwarding means adjacent the front of the conveying means adapted to engage the face of each leading sheet adjacent a side edge thereof and forward said sheet laterally and in standing position from said conveying means; and means for positioning each sheet on the conveying means so that a side edge thereof will be in a definite position for action of said sheet forwarding means.

48. In apparatus for removing sheets from the type of conveying means which receives sheets one after another at the rear thereof and supports and conveys a supply of the sheets standing on edge one behind another: the combination of suction sheet forwarding means adjacent the front of the conveying means adapted to engage the face of each leading sheet adjacent a side edge thereof and forward said sheet laterally and in standing position from said conveying means; and means for moving each sheet sideways to a predetermined position prior to delivery of said sheet to the conveying means so that a side edge thereof will be in proper position for action of said suction sheet forwarding means.
